Primary Examiner — Michael C Stout*Assistant Examiner* — Fitzgerald L Butac(74) *Attorney, Agent, or Firm* — H.C. Park & Associates, PLC(57) **CLAIM**

The ornamental design for a robot for delivery, as shown and described.

DESCRIPTION

FIG. 1 is a front, right perspective view of a robot for delivery, showing our new design.

FIG. 2 is a rear, left perspective view of the new design.

FIG. 3 is a front view thereof.

FIG. 4 is a back view thereof.

FIG. 5 is a right side view thereof.

FIG. 6 is a left side view thereof.

FIG. 7 is a top-view thereof.

FIG. 8 is a bottom-view thereof.

FIG. 9 is a rear, left perspective view of the robot for delivery with a lid in an open position in a state of use; and, FIG. 10 is a front, right perspective view of the robot for delivery with a lid in an open position in a state of use. The broken lines show portions of a robot for delivery that form no part of the claimed design.

1 Claim, 10 Drawing Sheets(56)
